UNITED STATES PATENT OFFICE.

GEORGE J. BOTT, OF COLUMBUS, OHIO.

DESIGN FOR A COMBINED BRIDGE-HOOK AND CHALK-HOLDER.

41,469.

Specification for Design.

Patented June 13, 1911.

Application filed March 18, 1911. Serial No. 615,445. Term of patent 7 years.

To all whom it may concern:

Be it known that I, GEORGE J. BOTT, a citizen of the United States, residing at Columbus, in the county of Franklin and State of Ohio, have invented a new, original, and ornamental Design for a Combined Bridge-Hook and Chalk-Holder, of which the following is a specification, reference being had to the accompanying drawing, forming part thereof, in which—

Figure 1 illustrates the combined bridge

hook and chalk holder in perspective, and Fig. 2 shows the same in side view.

I claim:

The ornamental design for a combined bridge hook and chalk holder as shown.

GEORGE J. BOTT.

Witnesses:

BENJAMIN FINCKEL,
MAYME FOARD.
